UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

APPARATUS FOR CRACKING HYDROCARBONS.

1,335,771.

Specification of Letters Patent.

Patented Apr. 6, 1920.

Application filed January 15, 1917. Serial No. 142,545.

To all whom it may concern:

Be it known that I, FRANK E. WELLMAN, a citizen of the United States, residing at Kansas City, in the county of Wyandotte 5 and State of Kansas, have invented certain new and useful Improvements in Apparatus for Cracking Hydrocarbons, of which the following is a specification, reference being had therein to the accompanying drawing.

10 My invention relates to apparatus for the treatment of hydrocarbons, and particularly to mixed series of hydrocarbons found in petroleum. It has for its object the production of apparatus which shall be more efficient, simpler, and safer than those heretofore in use.

The specific object of the present invention is to crack heavy oils so as to produce lighter oils, that is to say, to crack the heavy 20 petroleum products so as to produce gasoline and similar mixtures of lower specific gravity. The essential principle involved in this as in previous systems of my invention, is that of heating the oil while under pressure, or compressing it while being heated, until a desired critical point is reached in both temperature and pressure, at which the desired conversion takes place. This much is known in the art, being commonly referred to as the "heat and pressure 30 process." Various forms of apparatus have been designed for carrying the general process into effect, and many specific modifications have been proposed with respect to the 35 several steps involved, their duration, etc. All of these, however, so far as I am aware, have had to do with continuously operating systems, using this term, of course, in a broad sense, since in all systems it is necessary to interrupt the operation at stated 40 intervals for purposes of cleaning, allowing the retorts or stills to cool down, and for general inspection and repairs. There is a class of continuously operating systems, in 45 which intermittent steps are performed, such as that disclosed in United States Patents Numbers 342,564 and 342,565, granted May 25, 1886, to G. L. Benton. The purpose in that case, however, is different from 50 my present purpose, as will sufficiently appear hereinafter.

The distinguishing feature of the present invention lies in the fact that it is essentially and as to its main operation, intermittent. An ancillary but also very impor-

tant feature is that the system is automatic in operation, although, like other systems, it can be operated manually when necessary or desirable. Briefly stated, the apparatus comprises a retort or still adapted to resist 60 high temperatures and high pressures, with means for heating the same; a supply tank and a measuring tank in which the charge is placed under pressure in any suitable manner, as for example through the agency 65 of compressed air; a connection from the measuring tank to one end of the retort and a connection from the other end of the retort to condensing and receiving devices; and controlling valves and pipe connections so 70 adjusted that the method may be practised as follows: First, a charge, preferably of preheated oil, is admitted to the measuring tank and there placed under pressure. The discharge valve of the retort being closed, 75 this charge is forced into the retort, in which it is retained against back pressure by check valves, between which is interposed a protective device. The charge is heated in the retort, and the temperature and pressure 80 rise until the critical point is reached at which additional thermal energy is constantly taken up and transformed into work done in cracking or breaking down the molecular structure and arrangement of the 85 oil. Beyond this point the pressure increases, but the temperature remains fairly stationary and will so remain until the entire charge is cracked. Any increase in temperature beyond this point means that 90 the desired step of cracking is completed. At this critical point therefore I remove the converted hydrocarbon from the retort, and in order to do this with the greatest efficiency, and produce a maximum effect, I 95 provide for what I may call an automatic explosion. The pressure in the retort is caused to operate a series of valves controlling the inlet and discharge ports of the retort, as well as the admission of a fresh 100 charge to the measuring tank, and various details. When the pressure in the retort has risen to the critical point referred to, the discharge valve is suddenly opened and latched, and the entire contents of the retort 105 are permitted to forcibly blow out, carrying with them not only the converted hydrocarbons in bulk, but also what would ordinarily be regarded as residual carbon deposits, tar and the like, which otherwise would form 110

coky deposits on the walls of the retort. This blowing out not only cleans the retort, which may be regarded as an incidental step, but, more important, it produces a 5 powerful shock to the molecular equilibrium of the material under treatment. I am aware that in the Benton patents referred to, it is stated that by suddenly expanding the hot liquid into an enlarged chamber, complete vaporization of all of the constituents 10 takes place, but this is not the same thing that occurs in the present case. Cracking has taken place, with the formation of the usual percentage of fixed gases at the given 15 temperature and pressure, and the conversion of the balance of the liquid into lighter series with more or less admixture of very heavy residuum unconvertible without further treatment, and difficult to vaporize except at very high temperatures. This mass 20 is blown out and conversion is not only accelerated, but, so far as the convertible constituents are concerned, seem to be completed by the sudden shock.

25 As will sufficiently appear hereinafter, I employ the usual condensing and receiving apparatus, and I may employ also any suitable type of fractionating means or dephlegmator. I have not heretofore found it necessary 30 to blow out into an expansion chamber, but it is to be understood that I may do so should I find it to be necessary or desirable, without departing in the slightest degree from the principles of my invention.

35 A very important matter I have found in practice, and one upon which the success or failure of any given operation may depend, is the amount of oil placed in the retort at any given time. In operating the 40 old type coils or stills it has been observed that: First, with conditions apparently right for cracking, only a small conversion into gasoline was made; second, under the same conditions of pressure and temperature 45 as before a large conversion was made; third, under apparently the same conditions a large amount of fixed gases were produced, accompanied only by a small conversion of poor gasoline. These observed

50 facts were not understood until studied in the light of the present invention. In the first case the coil was too full of oil, so that while the temperature and pressure were right, there was not enough vapor space; 55 in the second case there was just enough oil in the retort and the proper space above it, that is to say, conditions were correct; while in the third case there was too little oil in the coil. Thus it will be seen there is a

60 specific relation between the volume of the oil under conversion and the space above which must be determined and controlled in order to make a good rate of conversion. Attempts to determine the temperature and 65 pressure relations, as hereinbefore stated,

have been made with fair success, but so far as I am aware it has not heretofore been possible to perfectly control the space relation, because of the continuing nature of the processes, and the more or less continuous 70 supply used in all the systems. On the other hand, in my present intermittent system, the spaced relation is controlled with more ease and certainty, so that a higher ratio of conversion may be attained. It is of course 75 possible to pump into the retort or coil continuously, and discharge the cracked products intermittently through a pressure release valve; but this valve would discharge variable amounts and would leave variable 80 amounts in the cracking still, so that the spaced relation would be variable and uncontrolled.

85 My experiments up to this time indicate that the oil should fill about one-fourth of the total space in the coil or retort in order to crack distillate at the temperature and pressure which I consider the most desirable. As an example of the conditions and results attained, the following recent trial 90 may be cited: The operation involves a charge of distillate at 38° B., which it will be apparent to those skilled in the art is extremely difficult to crack into gasoline. The retort employed was a pipe still in 95 several tiers, in a furnace carefully regulated to give approximate distributed and uniform temperature throughout. The pressure reached was the comparatively low pressure of six hundred pounds. This is 100 much lower than has been used in previous successful operations, and my present theory is that it was due to the cracked vapors rising to the upper convolutions of the pipe, into a comparatively cooler zone. By maintaining constant temperature and therefore 105 a high pressure in the upper as well as the lower tiers of pipe, at least a forty per cent. conversion can be made by this intermittent operation, but from purely commercial considerations, and character of the materials to be treated, it would seem to be more 110 economical and more efficient to operate on the basis of the following chart, which represents the particular operation referred to. 115 The temperatures and pressures given are those occurring in the processing of a batch, the temperature and pressure varying with the following simultaneous values and order of time.

120 First sample 25% gasoline of 62.2° B.
Last sample 35% gasoline of 64.2° B.
Average 32% gasoline of 63.7° B.

Temperature.	Pressure.	125
806	100	
850	200	
875	300	
875	400	
885	600	130

One feature of the invention to be herein more specifically described consists generally in the provision of upwardly extending expansion chambers, or "risers" connected 5 with the retort or cracking tube. These risers act more or less as fractionators, and a gasolene of a very good gravity may be secured directly thereby. The cracking and 10 expansion being coincident, natural separation by gravity will take place as the lighter molecules attain their maximum vibratory speed. What may be called natural fractionation will therefore ensue by merely drawing off from the tops of the risers or 15 expansion tubes into a suitable cooling coil or condenser. In this case, a valve for disturbing the equilibrium and drawing off the gasolene is placed between the tops of the risers and the cooling coil. By slightly 20 opening this valve in operation, a very good gravity of gasolene can be drawn off, and by so removing the gasolene vapors, the pressure may be maintained uniform. Assuming a definite pressure, the production 25 of more gasolene would increase this pressure, but by removing the excess gasolene from time to time, the pressure is never permitted to rise beyond a predetermined limit. When the required amount of gasolene is 30 secured, the valve is closed and the residue allowed to be blown out through a suitable conduit connected at the bottom of the retort.

I shall herein describe and illustrate several specific forms of my invention. I wish it distinctly understood, however, that these are not thus described and shown for purposes of limitation, but only for clarity of definition. In addition to the suggestions 35 hereinbefore made, many others will readily occur to those skilled in the art after reading this description and all such non-essential modifications or changes as are fairly within the scope of the appended claims are contemplated by me and are intended to be made use of in practising this invention. For example, I may use various known types 40 of apparatus elements, such as may be obtained in the open market, in place of those 45 shown herein and capable of subserving the required functions.

My invention is illustrated in the accompanying drawings in which,

Figure 1 is a diagrammatic view of a simplified form of my invention.

Fig. 2 is a diagrammatic view of a modification, making use of a pneumatic relay system.

Figs. 3 and 4 constitute a diagram of a further elaboration of the system.

Fig. 5 is a detail view of the leak or bypass valve used in my system.

Fig. 6 is a diagram showing expansion tubes.

Fig. 7 is a detail view indicating a pre-

ferred arrangement of an expansion tank when used with the apparatus of Fig. 1.

Referring in detail to the drawings, and particularly to Fig. 1, 1 indicates a supply tank for the hydrocarbon to be treated, 70 which tank is equipped with a pop valve 2 and a vacuum valve 3. This supply tank is also provided with suitable means 4 for preheating the contents to a predetermined point which, of course, is below its boiling 75 point. A pipe 5 leads from the supply tank to a pump 6 discharging into the supply line 7 which leads through a diaphragm valve 8, check valve 9, and float valve 10 into the interior of the measuring tank 11. The 80 various diaphragm valves are here shown in simple diagrammatic form for the sake of clearness, it being understood that they typify any pressure operated valve capable of being adjusted to respond to predetermined pressure, which devices are classic in the art. The float valve 10 is controlled by a suitable float 12 and so arranged as to be open when the float is down and closed when the float is up. The pump 6 is arranged to maintain the pressure in the supply line 7 at a constant predetermined point in a manner well known in the art. By the term diaphragm valve I indicate a valve 85 in which the valve stem is connected to a diaphragm operated by fluid pressure, and although I have shown this type of valve throughout the diagrams, it is to be understood that other types capable of performing a similar function may be used in their 90 place, such as a piston operated valve, or in fact any form of fluid relay.

A gage glass 13 is provided for the measuring tank 11 and also an air reservoir 14 connected therewith through a pipe 15 for 105 a purpose to be hereinafter explained. Pressure in the reservoir 14 is kept at a constant predetermined point, below that maintained in the supply line 7, by means of a suitable constant pressure pump 16. 110 The measuring tank 11 discharges at its lower end, and is there provided with a ball float valve 17 whose function is to trap the air in the tank after the oil passes out of the same and thus prevent the air from entering other parts of the system. The liquid discharged from the tank passes through the charging pipe line 18 into the cracking tube or retort 19. This tube is constructed 115 so as to resist the cracking temperature and pressure, both of which in this system are relatively high. The charging pipe line 18 contains a manually operated valve 20, a normally open diaphragm valve 21, and check valves 22 and 23, interposed in the 120 line of travel of the oil in the order named. Between the check valves 22 and 23 and between the check valve 23 and the cracking tube 19, the charging line 18 connects with safety or pop valves 24 and 25, respectively. 125

I find in practice that the cracking tube 19 operates most efficiently when filled to approximately one-fourth of its capacity, and for this reason the measuring tank 11 is so proportioned, and the float 12 so regulated that the tank will automatically fill to an amount equaling approximately one-fourth of the capacity of the tube 19 before the valve 10 operates to shut off the supply. By the term normally open diaphragm valve I indicate a valve in which the parts are so arranged that the passage controlled thereby will remain open when the pressure on the diaphragm is zero or below a predetermined actuating pressure, and in which the passage will be closed upon the application of the predetermined actuating pressure on the diaphragm.

The discharge end of the cracking tube 19 is provided with a ball float valve 26 for the purpose of retaining some gas pressure in the tube after discharge of the liquid, and, to take off excess gas pressure after closure of the float valve, a leak or bleed duct 27 is connected directly with the cracking tube 19 and with the discharge line 28 which is in communication with the discharge end of the cracking tube through the float valve 26. A pop valve 29 is included in the discharge line 28, and so arranged and adjusted as to open upon a predetermined pressure, which is the pressure reached at the time of the completion of the cracking of a given charge in the cracking tube. The discharge line 28 leads into a condenser 30, from whence the condensed product is led through a pipe 31 into a suitable receiving tank 32. If desirable the discharge pipe 28 may be connected to an expansion chamber as indicated in Fig. 7. In order to hold the pop valve 29 unseated during the discharge of the cracking tube, I provide the diaphragm operated trigger 33 arranged to be normally out of the path of a catch on the stem of the pop valve 29, but to be moved into the path thereof upon the application of a predetermined operating pressure on its operating diaphragm 34. This diaphragm 34 as well as the diaphragms of the valves 8 and 21 are connected to a common operating pipe line 35 which is connected with the cool end of the cracking tube through the charging line 18. A control valve 36 is interposed in the operating pipe line 35 between the cracking tube and the various operating diaphragms heretofore mentioned, which controlling valve is of the diaphragm operated type and has its operating diaphragm connected through a tube 37 to the operating line between the valve 36 and the cracking tube. The cracking coil 19 is mounted in a suitable oven or furnace 38 and supplied with heat by suitable heating means, preferably an oil burner such as 39. The level of the liquid

in the tanks 11 and 58 and retorts 19 and 48, and the positions of the various float valves during the treatment of a batch of material, are indicated in dotted lines in Figs. 1 and 2.

The operation of the system shown in Fig. 1 is as follows:

At the outset with no heat applied to the cracking coil 19, there would be no pressure in the operating line 35 so that the trigger 33 would be in its retracted position, the valve 21 open and the valve 8 closed. To initially fill the measuring tank 11, the normally closed valve 8 may be temporarily blocked open by placing a suitable object 80 through the opening 800 in the spring casting under the spring abutment on the valve stem, or it may be shunted through a bypass 40, indicated in dotted lines. As the air supplied to the measuring tank 11 from the reservoir 14 is at a lower pressure than that maintained in the supply line 7, the preheated hydrocarbon from the supply tank 1 is, through the automatic action of the pump 6, forced through the check valve 9 and float valve 10 into the measuring tank 11. When the measuring tank receives the predetermined volume of oil for the batch to be treated, the float valve 10 is closed and the supply pump 6 automatically stopped. The presence of a full measured batch in the measuring tank is indicated in the gage 13, and the valve 20 may now be opened and the oil burner 39 started, from which point on the operation becomes automatic. Under force of the compressed air from reservoir 14 the charge of oil in the measuring tank 11 is forced down through the charging line 18 into the cracking tube 19, passing through valves 21, 22 and 23, the check valves 22 and 23 being arranged to pass the fluid only in the direction indicated by the arrows thereon. As the tube 19 fills the pressure therein rises gradually. After the charge has passed out of the measuring tank, it rises to a point slightly above that in the reservoir 14 due to the heating up of the cracking tube, the charging line being closed against back pressure by the check valve 23. This increase of pressure acting through the operating line 35 causes the valve 21 to close, cutting off the supply tank, after which, the pressure continuing to rise to the predetermined point to which the diaphragm valve 8 is set to operate, causes this valve to open, whereupon the measuring tank is again filled with the preheated hydrocarbon from the supply tank in the manner before described. Upon a further increase of pressure in the cracking tube the diaphragm 34 is acted upon through the operating line 35 to move the trigger 33 into the path of the catch on the stem of pop valve 29.

When the pressure rises a little above this last predetermined point, the diaphragm

valve 36 is actuated to cut off the operating line 35 from the cracking tube so as to protect the low pressure diaphragms from the subsequent increase in pressure in the cracking tube 19.

The hydrocarbon in the cracking tube then continues to heat up, the pressure increasing, until cracking begins, when the temperature of the hydrocarbon becomes substantially constant while the pressure continues to rise. When the pressure finally reaches the predetermined point to which the pop valve 29 is set, the pressure exerted thereon through the cracking tube end of the discharge line 28, the float valve 26 being at this time off its seat, causes the pop valve 29 to open and to be held open by the engagement of the trigger 33 with the catch on the valve stem. Immediately upon opening of the pop valve the contents of the cracking tube are forcibly discharged out through the chamber of the float valve 26 and the discharge line into the condenser. This forcible discharge carries with it any carbon or other precipitate that might have formed in the tube or other parts of the apparatus in its path. Thus, an automatic cleaning of the apparatus is effected. The mixture of liquids and vapor cooling and condensing in the condenser 30 passes on through the pipe 31 into the receiving tank 32. As the cracking tube discharges the ball of the float valve 26 descends to its seat, trapping some gas in the cracking tube, excess gas pressure being relieved through the leak or bleed tube 27. When the pressure in the cracking tube drops to the predetermined point for which the diaphragm valve 36 is set, this valve opens again connecting the operating line 35 with the cool end of the cracking tube, and the pressure dropping farther to the points to which the diaphragm valves 21 and 8 and the operating diaphragm 34 are set, the trigger 33 is retracted, permitting the pop valve 29 to close, the valve 8 is closed and the valve 21 is opened. Immediately upon the opening of the valve 21 the cracking tube is recharged from the measuring tank 11, and the cycle of operation is automatically repeated.

The purpose of the check valve 22 is to trap any leakage through the check valve 23 until the pressure between the two rises sufficiently to operate the relief or pop valve 24. The pop valve 25 is connected with the charging line 18 between the diaphragm of the valve 36 and the cracking coil to protect the said diaphragm from excessive pressure.

Referring now to Fig. 2, this shows a system similar in all respects to that shown in Fig. 1, except that the valves 41 and 42 controlling, respectively, the charge and discharge of the cracking tube are operated through a pneumatic relay in the form of a diaphragm operated valve 43. The valve 43 is the same as that shown in Fig. 5, that is, it

is provided with a waste or bleed duct 44 arranged to be brought into communication with the exit chamber 45 of the valve, upon the closure thereof, through a duct 46 in the valve stem to relieve pressure at the discharge end of the valve and parts connected thereto. As used in the system of Fig. 2, the valve 43 is connected to be operated through the operating pipe line 47 in response to a rising of pressure in the cracking tube 48 to the predetermined point at which the valve is set, and to control the connection through the pipe 49 between the air reservoir 50 and the air line 51. The valve 43 is also arranged to be normally closed, and to open only upon the application of a predetermined pressure to its operating diaphragm, operating upon closure to open the bleed duct 44 to relieve pressure in the air line 51.

The operation of the arrangement of Fig. 2 is as follows: Assuming that the measuring tank 58 has been filled with the required charge, and that the pressure in the cracking tube is below that required for the operation of the air valve 43, compressed air will be supplied to the air line 51 from the reservoir 50 at a constant predetermined pressure maintained in a manner as that described for the reservoir 14 of Fig. 1, and this pressure in the line 51 causes the normally closed diaphragm valve 41 to be held open and at the same time operates the diaphragm 52 to hold the trigger stud 23 out of engagement with the valve stem of the discharge pop valve 42. This condition obtaining, the hand operated valve 13 is opened permitting the charge of hydrocarbon from the measuring tank to be forced into the cracking tube 48 in the same manner as that described in Fig. 1. As the tube fills the pressure therein increases and consequently the pressure in the operating line 47 until the pressure reached is a little above that in the reservoir 50, whereupon the diaphragm valve 43 is actuated to disconnect the air line 51 from the reservoir and to permit the air therein to escape, thus reducing the pressure and allowing the trigger 23 to move back into the path of the valve stem of the valve 42 and also permitting the valve 41 to close. When the pressure in the tube 48 reaches the point to which the normally closed diaphragm valve 53 is set, this valve is caused to open, permitting a recharge of the measuring tank 58 with preheated hydrocarbon from the supply tank 54. Upon further increase of pressure the valve 56 is closed to protect the valves 43 and 53 from the subsequent rise in pressure as the cracking tube heats up. The temperature of the contents of the cracking tube then continues to rise, and also the pressure, until cracking takes place, after which the further rise in pressure to the point to which the pop valve 42 is set causes this valve to operate and per-

70

mit a discharge of the contents of the cracking tube in the same manner as that described for Fig. 1. As the tube 48 discharges, and the pressure decreases, the 5 valve 56 first opens to reconnect the operating line 47 with the cool end of the cracking tube, after which valve 53 closes and after it valve 43 opens. Closure of the valve 53 disconnects the measuring tank from the 10 source. The opening of valve 43 again connects the air line 51 with the reservoir 50 which opens the diaphragm valve 41 and actuates the diaphragm 52 to push the trigger stud out of engagement with the catch 15 on the stem of the pop valve 42, permitting the valve to close. The measured batch in the measuring tank is now driven through the charge line into the cracking tube by the pressure of the air supplied from reservoir 20 50 through pipe 59, completing the cycle of operation which will be automatically repeated.

In Figs. 3 and 4 is shown a still further elaboration of my system in which a positively actuated discharge valve is used instead of the discharge pop valve of Figs. 1 or 2, and a diaphragm relief valve is used in place of the leak valve shown in Fig. 5.

Referring in detail to the arrangement of 30 the apparatus of Figs. 3 and 4, 60 is the pre-heater which leads through the pipe 61 to the automatic constant pressure pump 62, discharging through the pipe 63 into the measuring tank 64 through a diaphragm 35 valve 65 and a float valve 66. The constant pressure pump is arranged to maintain a constant pressure in the pipe line 63 through 100 operation of the pressure controlled valve 102 controlling the supply of steam through 40 the pipe 102 in response to variations in pressure in the pipe 63, all in a manner well known to those skilled in the art. The measuring tank 64 is provided with a gage glass 65', constant pressure air reservoir 66' 45 connected through pipe 67 with the interior thereof, and a lower float valve 68. Pressure is maintained in the reservoir 66' by means of a steam pump 69 supplied with steam through the pipe 70 and controlled in 50 response to a change of pressure in the reservoir 66' by means of the diaphragm valve 71. A charging pipe line 72 leads from the 55 exit end of the float valve 68 to the cracking tube 73 through the diaphragm valve 74 and check valve 75. The portion of the charging pipe line 72 between the valves 74 and 75 is connected with a relief or pop valve 76 to relieve any pressure that might accumulate between the valve 75 and the valves 74 60 and 68. A float valve 77 which is like that shown at 26 in Fig. 1, and bleed duct 78 are provided at the discharge end of the cracking tube 73 and connected with a discharge pipe line 79 containing a diaphragm valve 65 80 and from the exit side of which it leads

through a condenser or cooler 81 to a receiving tank 82. An operating pipe line 83 connects directly with the cracking tube 73 and connects in common with the diaphragms of the diaphragm valves 65, 80, 84 and 85. The 70 valve 84 is a normally open valve and controls the connection between the air line 86 and the air reservoir 87. A hand operated throttle or valve 88 is also interposed in this connection. Constant pressure is maintained in the reservoir 87 by means of the steam operated pump 89 whose steam supply through the pipe 90 is controlled by the diaphragm valve 91 operated in response to variations in pressure in the reservoir. 80 The diaphragm valve 85 is a normally closed valve and operates as a relief valve for the air line 86. The air line 86 is connected with the diaphragms of the valves 74 and 92. Valve 92 is a normally closed valve and 85 controls a by-pass around the check valve 93.

The operation of the system shown in Figs. 3 and 4 is as follows:

The preheater 60 is supplied with the hydrocarbon to be treated and heated up to 90 the predetermined temperature below that of its boiling point, which temperature is to be maintained during the operation of the devices, and upon this temperature being reached power is supplied to the pump 62 95 which starts operating to fill the measuring tank 64, the valve 65 being temporarily blocked up through the use of any suitable means capable of holding the valve stem in its open position, or it may be shunted 100 through a by-pass such as 44. When the measuring tank is filled the valve 88 is opened to connect the air line 86 with the reservoir 87. Air under pressure now passes through the normally open valve 84 into 105 the air line causing valves 74 and 92 to open. The opening of valve 92 at this point in the cycle has no effect, but the opening of valve 74 permits the measured charge in the tank 64 to be driven under pressure of the air 110 from reservoir 66' through the charging line 72 into the cracking tube. When the measuring tank 64 empties to within a short distance of the inlet end of the float valve 68, this valve is closed by the downward 115 movement of its operating float, thus preventing the entrance of air from the measuring tank into the system. The fire is now started in the oven or furnace 95, and as the temperature in the cracking tube rises 120 the pressure also rises, and when the latter reaches a point a little higher than that in the air reservoir 66' this pressure, transmitted through the operating line 83, operates the diaphragm valves 84, 85 and 65, in the 125 order named, the time element being obtained by setting the valves to operate on slightly varying pressures. The closure of valve 84 disconnects the air line 86 from the reservoir 87, the opening of valve 85 re- 130

leases the compressed air from the air line, and the opening of valve 65 permits the measuring tank 64 to be again charged by the automatic pump 62. The temperature 5 and pressure in the cracking tube now continue to rise until cracking begins, when the temperature becomes approximately constant, and the pressure continues to rise until it reaches the predetermined point at 10 which the valve 80 is set. When this point is reached, pressure transmitted through the branch 83' of the operating line 83 to the operating diaphragm of the valve 80 causes this valve to open, permitting the discharge 15 of the contents of the cracking tube through the discharge line 79 to the condenser 81 and receiving tank 82. At the moment this discharge begins, the pressure in the cracking tube will, of course, begin to fall, and 20 check valve 93 prevents the release of pressure from the diaphragm of the valve 80 back into the cracking tube, until the pressure has dropped to the predetermined point at which the valve 84 is set, where- 25 upon this valve is opened, again connecting the air line 86 with the reservoir 87. Immediately after the opening of valve 84 the relief valve 85 is closed, and immediately after this, valve 65 is closed. Closure of the 30 relief valve 85 permits the air pressure to rise in the air line 86, thus opening valves 92 and 74. Immediately upon the opening of valve 92 the pressure on the diaphragm of valve 80 is released, causing this valve 35 to close. The opening of valve 74 permits the cracking tube to be recharged from the measuring tank 64, after which the cycle of operation is repeated automatically.

While I have here shown the operation of 40 my system entirely automatic, it will be obvious that part or all of the cycle of operations may be controlled by hand. It is also obvious that various parts may be made adjustable to compensate for variations in 45 working conditions and the qualities of hydrocarbons to be treated. For example, the measuring tank may be made adjustable to vary the size of the batch to be treated and the diaphragm valves, or other pneumatic 50 relays that might be used, may be made adjustable to operate on different pressures so as to effect variations in time and temperature. Again, in practice, the system is not limited to the use of a single straight crack- 55 ing tube, but may make use of any form of cracked retort. Also, other measuring devices may be substituted for the measuring tank, such as a measuring pump, a meter in the charging line arranged to control a valve 60 in the charging line, or any other automatic measuring device that would readily occur to those skilled in the art.

Among the advantages of the system dis- 65 closed are, that a certain amount of oil is put into the cracking tube each time and as

the valve controlling the discharge of the tube is controlled by the pressure which is dependent on temperature, thus making the discharge valve a thermal safety relief, the tube cannot overheat; the violent discharge 70 of the contents of the cracking tube through the discharge valve sweeps all free carbon with it, thus preventing the formation of hard coke deposits; the chance of an explosion is materially lessened and the danger 75 from any that might occur is eliminated by reducing the treatments to comparatively small batches, permitting the use of extremely high pressure which is of great advantage as a more superior gasoline can be 80 obtained where the hydrocarbons being treated are kept largely in a liquid state and the pressure necessary to keep them down in a liquid state under favorable cracking conditions is extremely high; the sudden relief 85 of pressure on the hydrocarbon while at a high temperature is found to bring about a disturbance of the equilibrium which acts to increase the percentage of conversion; the retention of some of the fixed gases in the 90 tube after each discharge enables the pressure to be built up for recharge, by the compression of the gas retained and at the same time lessens the amount of free gas generated and the amount of heat required. 95

Fig. 6 shows the expansion tubes or "risers" 605 referred to in the preliminary or general statement of the invention. The charging and discharging pipes are indicated by short broken sections only. With 100 the arrangements for distributing the equilibrium which I have shown in this figure, there is no reason why the yield could not be forced to forty-five per cent. It will be noted I have shown a valve 606 at 105 the top of the cooling coil 607 immersed in water, and thus I am able to effect condensation with or without pressure. Another advantage is that the operation of the valve 606 at the top of the cooling coil as also 110 shown in Fig. 6, will leave the coil empty when I have finished drawing off, and the space in the cracking coil or retort will be filled with uncracked vapor when the pressure is built up on the next reaction, and thus the cooling coil 607 will be filled with the uncracked material or the natural vapors. I have this cooling coil contain just enough space to hold the amount that I want to draw off. I can thus close the top 115 valve, build up conditions in the retort suitable for cracking, then open the top valve, allowing the cooling coil to condense full, and thus literally trap off gasoline. The top valve being closed before I blow the residue 120 from out the retort, the contents of the cooling coil will not be expanded back into the retort when the release takes place. I can also employ with the apparatus of Fig. 6, a fractionator such as indicated at 600, con- 125 130

necting said fractionator at the top of the risers, instead of piping off directly from them. To make this connection the normally open valve 601 is closed and the normally closed valves 602, 603 and 604 are open. This, however, is not required except when it is found that the risers do not provide sufficient fractionation in themselves. I prefer to blow out through the 10 end of the retort in the same manner and by the same means indicated in the other figures.

After reading this specification, my statements regarding the theory of operation will 15 be better understood. It appears that a continuous equilibrium of heat and pressure does not do the work; but when this equilibrium is suddenly broken up or destroyed, the disintegration curve turns sharply up- 20 ward. When properly done, the disturbance of equilibrium has remarkable results, giving as high as 45 per cent. conversion into gasoline at one treatment.

With a cylindrical container, such as illustrated in the drawings, any amount of gas, 25 may be retained, consequently when the new charge is inserted, the pressure, as stated, is built up with the compression of the gas retained. Assuming that I blow off until 30 the gage registers only 100 pounds, the container is then free from liquid hydrocarbons with the possible exception of a few very high boiling-point fractions, but it still holds gas at a pressure of 100 pounds. I 35 may now insert one-third capacity of oil, which would raise the pressure to 133 pounds; and this is the pressure with which I start operating; obviously much nearer a point of equilibrium than the low or zero 40 pressures heretofore available. The results are, less free gas generated, a lower temperature required, a higher conversion, and better gasoline.

One advantage which is of the greatest 45 importance in practice is the removal of the carbon with each batch of the cracked material. It has been assumed to be impossible to crack oil into gasoline without having the precipitated carbon collect on the walls 50 of the container in which the cracking is done. Based on calculations made in connection with my apparatus, it has been determined that a uniform film of carbon .005 inch will cut down the efficiency of operation 55 to five per cent. of normal. In other words, this thin film will require twenty times the normal amount of heat to be used for the same operation, with the result that in order to maintain any efficiency at all, the pipe 60 must be overheated, and is ultimately destroyed in whole or in part. From personal experience, I believe that the coil approaches the danger line when the soot is $\frac{1}{16}$ inch in thickness, but its usefulness is greatly reduced long before that limit is reached.

The deposit of soot or carbon is prevented in substantially its entirety by the use of my present method. At the pressures employed, largely over 700 pounds to the square inch, when the pop valve or release valve opens, 70 there is an instantaneous violent explosion, and the jar of this explosion removes all of the adherent carbon and throws it out in the stream of oil.

It will be observed that I attain automatic 75 control of the pressure by means of the blow-off valve, and automatic control of the space relation in the retort between the oil and the gas or vapor therein, by means of the measuring tank. With respect to the 80 temperature, it may be said that this remains constant, with proper control, after a cracking degree of temperature is once attained. Additional increments of heat energy are taken up continuously in the 85 work of disintegrating or breaking down the molecular structure and arrangement of the heavy hydrocarbons. The normal point for each kind of oil treated will soon 90 be found, and after a certain period of heating, if the actual temperature of the oil rises, it will be an indication that molecular equilibrium has been established and cracking, completed and at a standstill, all added heat units thereafter going to raise the 95 actual temperature of the entire mass in the retort. As this means to increase the elastic forces or tendency to expand, it indicates a rise in pressure which would be dangerous were it not for the automatic valves which 100 check the pressure by emptying the retort preferably, as I have heretofore explained, leaving the fixed gases under a certain pressure, which will form the initial pressure for the next succeeding charge of oil. The 105 existence of this initial pressure does not of course save any energy, but it does economize time in raising the charge to cracking heat and pressure.

A commercially desirable feature which 110 I have not specifically described herein, because in itself it forms no part of the present invention, but which is mentioned here as an example of refinements in the use of the invention, is a dephlegmator or fractionator, connected to receive the cracked products from the retort and to fractionally condense the same and deliver them either to receiving tanks direct, or if further cooling be required, to ordinary condensers or 115 coolers. Apparatus of this general type is illustrated and described in my prior applications: Serial No. 32,704, filed June 7, 1915; Serial No. 50,775, filed Sept. 15, 1915; Serial No. 69,499, filed Dec. 30, 1915; Serial No. 69,500, filed Dec. 30, 1915; Serial No. 110,795, filed July 22, 1916; and Serial No. 126,971, filed Oct. 21, 1916. Any of the foregoing apparatus can be applied in the 120 present case either in place of the con- 125 130

denser or between the condenser and the pressure retaining valve at the discharge end of the retort. If a fractional evaporator be employed such as described in application Serial No. 126,971, filed Oct. 21, 1916, no other expansion chamber would probably be needed, and the same might be true with a dephlegmator having a cylindrical chamber of large dimensions; but with any of 5 the remaining types, involving the use of coils of pipe or the like of relatively small diameter, it will probably be necessary to interpose an expansion chamber between the discharge end of the retort and the fractionator. This expansion chamber may take 10 the form of a vertical cylinder of some height, or any other desired form provided that its capacity is sufficient to permit a multiple expansion of the oil and vapors 15 blown out of the retort so as to substantially reduce the pressure before it encounters the resistance of the small bore pipes. If the discharge end of the fractionating and condensing system be opened 20 to the atmosphere the effect would not be so great, and if all piping be made strong enough to withstand the discharge pressure, then the expansion chamber may be reduced 25 in size or eliminated.

Having thus described my invention what 30 I claim and desire to secure by Letters Patent is:

1. Apparatus for treating hydrocarbons comprising the following instrumentalities, 35 a retort having charging and discharging ports, valves for said ports, means for heating the retort and an automatic pressure operated relay valve connected on its controlled side to the retort and connected on 40 its controlling side to said discharge valve, to operate the latter at any pressure for which the relay may be set.

2. Apparatus for treating hydrocarbons comprising the following instrumentalities: 45 a retort having charging and discharging ports, valves for said ports, means for heating the retort, and an automatic pressure operated relay valve connected on its controlled side to the retort and connected on its 50 controlling side to the discharge valve, to open the latter at any predetermined pressure in the retort, together with a latch for

said discharge valve and a controlling connection for said latch to the controlling side of said relay.

3. Apparatus for treating hydrocarbons comprising the following instrumentalities: a retort having charging and discharging ports, valves for said ports, means for heating the retort, and an automatic pressure operated relay valve connected on its controlled side to the retort and connected on its controlling side to both the charging and discharging valves, said valves being set for opposite conditions, whereby the charging 60 valve will be closed when the discharging valve is opened and vice versa.

4. Apparatus for treating hydrocarbons comprising the following instrumentalities: a retort having charging and discharging 70 ports, valves for said ports, means for heating the retort, and an automatic pressure operated relay valve connected on its controlled side to the retort and connected on its controlling side to both the 75 charging and discharging valves, said valves being set for opposite conditions, whereby the charging valve will be closed when the discharging valve is opened and vice versa, together with means for measuring a charge, 80 also controlled by said relay valve, and means operably to force said charge into the retort when the charging valve is opened.

5. Apparatus for treating hydrocarbons comprising the following instrumentalities: 85 a retort having charging and discharging ports, valves for said ports, means for heating the retort, and an automatic pressure operated relay valve connected on its controlled side to the retort and connected on its controlling side to both the charging and discharging valves, said valves being set for opposite conditions, whereby the charging valve will be closed when the discharging 90 valve is opened and vice versa, together with 95 means for measuring a charge, also controlled by said relay valve, and means for forcing said charge into the retort under initial pressure sufficient to overcome residual pressure of gases left in the retort after 100 discharging.

In testimony whereof I affix my signature.

FRANK E. WELLMAN.
